UNITED STATES PATENT OFFICE.

JOSEPH F. SCHIMEK, OF WORCESTER, MASSACHUSETTS, ASSIGNOR, BY MESNE ASSIGNMENTS, TO WHITIN MACHINE WORKS, OF WHITINSVILLE, MASSACHUSETTS, A CORPORATION OF MASSACHUSETTS.

METHOD OF AND APPARATUS FOR TRANSFERRING CARDED MATERIAL.

Application filed April 9, 1927. Serial No. 182,408.

My invention relates generally to the art of carding and has for its object to provide an improved method of, and apparatus for, transferring carded material, such as wool, 5 cotton, or other staple from one carding machine to another.

In Patent No. 1,610,209, issued to me on December 7, 1926, there is shown and described a method of, and apparatus for, transferring carded material, which is characterized by the distribution of the cardings from the doffer cylinder of the first machine to oppositely moving receiving aprons which blend the cardings into a web for transfer to the feed table of the second carding machine. As set forth in my above mentioned patent, the cardings are distributed obliquely with respect to the oppositely moving receiving aprons, whereby the cardings are gathered into 10 a web, the edges of which are thinner than at the middle thereof, so that when the web is laid on the receiving table of the second carding machine adjacent folds are in nesting relation. In operation, the apparatus of my 15 aforesaid patent is adapted to form a loose web without substantial disturbance of the parallel relation of the fibres, so that quality of the staple is preserved when the web is acted on by the second card, and means are 20 also provided for varying both the width and thickness of the web to meet varying conditions of operation and quality of staple.

According to the present invention, I provide a carding apparatus that operates on somewhat the same general principle as the apparatus shown in my aforesaid Patent No. 1,610,209, the apparatus of the present invention being particularly characterized by its compactness and adaptability to meet conditions where the space between the ends of adjacent carding machines is limited. In the apparatus of the present invention, the cardings are taken directly from the doffer cylinder and distributed uniformly upon oppositely moving aprons which build the cardings into a web of uniform cross-section through their cooperation with gathering rolls located opposite the center of the doffer cylinder and below the aprons. The web is then conveyed, without twisting, to a point immediately above the receiving table of the second carding machine.

By my invention, width and thickness of

the web is adapted to be controlled through very simple adjustments of the receiving 55 aprons and their associated gathering rolls, and the entire apparatus is characterized by the fact that the distance which the cardings have to travel in being transferred from the doffer cylinder of the first machine to the feed table 60 of the second machine, is reduced to a minimum, all as will hereinafter more fully appear with reference to the accompanying drawings, in which—

Fig. 1 is a partially diagrammatic view, in 65 side elevation, showing my improved transferring apparatus in connection with parts of two carding machines.

Fig. 2 is a plan view of that portion of the apparatus for gathering the cardings and 70 building them into a web.

Fig. 3 is a view in front elevation showing that portion of the apparatus which is attached to the frame of the carding machine.

Fig. 4 is a diagrammatic view illustrating 75 the manner of driving the parts shown in Fig. 3.

Fig. 5 is an enlarged end view of the parts shown in Fig. 3.

Fig. 6 is a diagrammatic view illustrating 80 in plan the handling of the web from one carding machine to another.

Like reference characters refer to like parts in the different figures.

Referring first to Figs. 1 and 5, a portion 85 of the first carding machine is shown at A and comprises a main card cylinder 1 and a doffer cylinder 2 which is adapted to strip the carded fibres from the main cylinder 1. One end frame of the carding machine is indicated 90 at 3 and a shaft 4 is rotatably supported by the frame 1 with its axis parallel to the axis of the doffer cylinder 2. The shaft 4 provides a number of fingers 5 for carrying a doffing knife 6 and the shaft 4 is adapted to have an 95 oscillatory movement imparted thereto which will cause the knife 6 to remove the cardings in sheet form from the cylinder 2 as the latter rotates in the direction of the arrow and deliver them to the gathering and transferring 100 device which will now be described.

As best shown in Figs. 3 and 5 each frame 3 of the carding machine provides a bracket 7 for supporting the end portions 8^a of a beam 8 which extends all the way across the front 105 of the doffer cylinder 2. The beam 8 pro-

vides a number of slots 9 and 10 at different levels in which are received bearings 11 for supporting parallel shafts 12 and 13 in different horizontal planes. The shafts 12 and 13 carry rolls 14 and 15 respectively, and each pair of rolls 14 and 15 is adapted to support an apron 16, the aprons 16 being inclined upwardly in opposite directions.

As best shown in Figs. 1 and 5, in which the frame 3 has been broken away, the aprons 16 extend inwardly toward and underlie a shield 17 extending downwardly from the doffer cylinder 2 so that the knife 6 overhangs the shield 17; consequently the sheet 18 of cardings removed from the doffer cylinder 2 will slide down the shield 17 and fall on the aprons 16. The lower shaft 13 of each apron 16 carries a sprocket wheel 13^a around which passes a chain 18 adapted to be driven from a sprocket 19 on a shaft 20 located below the shaft 13. The shaft 20 is journaled in a bearing supported by the beam 8 and is connected by bevelled gearing 21 to a shaft 22 supported in front of the aprons 16 by brackets 23. The shaft 22 extends laterally in front of the member 8 and is adapted to be rotatably driven by gearing 24 from a countershaft 25. The shaft 25 is driven from a source of power, preferably derived from the carding machine, by means of a pulley 26, and it is obvious from Fig. 4, that when the shaft 22 is so driven, the upper surfaces of the aprons 16 will move toward each other, as indicated by the arrows.

The shaft 22 also carries a roll 27 between the brackets 23, and as best shown in Fig. 5, the roll 27 carries a belt 28 which extends rearwardly underneath the aprons 16, where it passes around a roll 29. The roll 29 is supported by extensions 30 of the brackets 23, and an idler roll 31 is also supported by the bracket extensions 30 with its periphery spaced from the belt 28 as it passes over the roll 29 back to the front roll 27. The rolls 29 and 31 are driven in unison and at the same speed as the roll 27 by means of a chain 32, see Fig. 2, passing around sprocket wheels 33 mounted on the shaft 22 and on the roll shaft 29^a, respectively. The roll shaft 31^a also carries a sprocket wheel 34, the lower periphery of which is engaged by the chain 32, so that the roll 31 will be driven in a direction of rotation opposite to that of the roll 29.

From a consideration of Figs. 1 and 6, it is evident that when the carding machine is operating to drive the shaft 22, the sheet of cardings from the doffer cylinder 2 will be removed by the vibrating knife 6 and will fall upon the oppositely moving surfaces of the aprons 16. The movement of the aprons 16 will tend to gather the cardings in the space at B between the ends of the aprons 16, from whence the gathered cardings will pass downwardly between the oppositely moving rolls 29 and 31. As this occurs the cardings

will be transformed from an arrangement in sheet form into a continuous web, the width of which is determined by the distance between the aprons 16 at B and the thickness of which is determined by the space between the rolls 29 and 31, or between the belt 28 and roll 31. The fact that the rolls 29 and 31 are positively driven in opposite directions, as indicated by the arrows, insures that the web will be delivered easily to the apron 28 which will in turn convey it to the front roll 27, which is turning in the same direction of rotation as the rear roll 29.

As indicated in Fig. 5, the belt 28 is very loose, the underside of the belt being supported substantially tangentially to the rolls 27 and 29 by means of a guard 35. By thus supporting the lower side of the belt 28 the upper surface thereof is relatively slack, so that the web is not closely pressed against the underside of the roll 31. In other words, the belt 28 is not necessarily driven at the same speed as the rolls 27 and 29, and in cases where very long staple is being handled the belt 28 may be even omitted. In this latter event, the guard 35 prevents the web from sagging too much as it passes from the roll 29 to the roll 27. The web is held to the upper surface of the roll 27 or belt 28 by means of a roll 36 supported between upwardly extending arms 37 of the brackets 23. An apron 38 passes around the roll 36 and extends upwardly around a roll 39 supported by a bracket 40 extending from a vertical post 41 carried by the beam 8. A second apron 42 extends parallel to the apron 38 and is supported at its top and bottom by rolls 43 and 44 respectively, while a third apron 45, supported on rolls 46 and 47, extends substantially at right angles to the aprons 38 and 42.

One end of the shaft 22 carries a pulley 48 which is connected by a belt to a corresponding pulley 49 on the shaft 50 of the roll 46. Consequently the apron 45 is driven in the same direction as the apron 38, that is, away from the carding machine, while the aprons 38 and 42 are driven in opposite directions from the shaft 50 to cause their opposed surfaces to move upwardly and confine the web therebetween.

The apron 45 is adapted to deliver the web to the receiving table 51 of a second carding machine, the web being distributed laterally on the table 51 by means of a reciprocating head 52 operated by mechanism which forms no part of the present invention, but is fully shown and described in my above mentioned Patent No. 1,610,209.

From a consideration of Fig. 1, which indicates diagrammatically the entire course of the carded material, it is obvious that when my apparatus is in operation the cardings are gathered into a flat web by the operation of the aprons 16 in conjunction with the rolls

29 and 31, the web being formed without substantial alteration of the parallel relation of the fibres of the cardings. As the web is formed at the rolls 29 and 31, it is carried 5 forward and upwardly without any of the twisting which has characterized the transfer of cardings in previous machines, this result being accomplished by the arrangement of all the conveying rolls on parallel axes. 10 Furthermore, the fact that the web is at substantially the center of the doffer cylinder 2 permits the web to be conveyed to a point substantially above the center of the feeding table of the second machine without 15 changing direction, in other words, in the shortest possible line of movement.

As previously pointed out, the width of the web is determined by the width of the space B between the aprons 16, and in order 20 to adjust this width, means are provided for shifting the pairs of rolls 14 and 15. To this end each bearing 11 is adjustable in its slot 9 or 10 by means of a stud 53 threaded into a lug 54 provided on the beam 8. By turning 25 a stud 53 the entire bearing and shaft may be shifted laterally within the slot 9 or 10, so that the space B between the aprons 16 can be very accurately adjusted to control the width of the web being formed.

50 I claim,

1. In apparatus of the class described, the combination with the doffer cylinder of a carding machine, of a pair of converging and downwardly moving aprons, having a substantial gap therebetween, and spaced surfaces located in the gap beneath said aprons movable about axes parallel to the axis of the doffer cylinder, whereby to gather carded material into a ribbon, the width of which is 35 determined by the gap between said aprons.

2. In apparatus of the class described in claim 1, a pair of aprons, rolls over which said aprons travel, a support for said rolls, and adjustable journals in said support, 40 whereby the rolls can be adjusted in position to vary the effective length of the aprons, or the distance therebetween.

3. In apparatus of the class described, the combination with the doffer cylinder of a 45 carding machine, of a pair of converging and downwardly moving aprons, having a sub-

stantial gap therebetween, and spaced surfaces located in the gap beneath said aprons movable towards each other about axes parallel to the axis of the doffer cylinder, whereby to gather carded material into a ribbon, the width of which is determined by the gap between said aprons and the thickness of which is determined by the distance between said surfaces. 55

4. In apparatus of the class described, the combination with the doffer cylinder of a carding machine, and a pair of oppositely moving aprons having a substantial gap between the adjacent ends thereof for receiving a portion of the carded web from the doffer cylinder, of a pair of oppositely driven rolls located in the gap beneath said aprons, a third roll located in front of said aprons and a belt loosely extending between one of the first named rolls and the third roll, whereby the carded material delivered into the gap by the aprons is formed into a ribbon which is conveyed flatwise on said lower belt to a point in front of the gathering aprons. 65

5. The improvement in the handling of carded material, which consists in removing the carded web in sheet form from the doffer cylinder of a carding machine, immediately moving side portions of the carded web downwardly in opposite directions towards an undisturbed central web section where the side portions intermingle with the central section and then conveying the ribbon thus formed flatwise forwardly and upwardly to a position over a second carding machine, the said flatwise conveyal of the ribbon taking place in a straight line as viewed in plan. 80

6. The improvement in the handling of carded material which consists in removing the carded web in sheet form from the doffer cylinder of a carding machine, dropping a central section of the carded web directly upon surfaces moving away from the doffer cylinder and simultaneously gathering the remainder of the web on surfaces moving towards the central section, thus forming a flat ribbon the thickness of which is determined by the distance between the central conveying surfaces. 85

Dated March 30, 1927.

JOSEPH F. SCHIMEK.
